UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

MACHINE FOR ORNAMENTING LEATHER.

1,115,184.

Specification of Letters Patent. Patented Oct. 27, 1914.

Application filed December 17, 1913. Serial No. 807,292.

To all whom it may concern:

Be it known that I, HERBERT E. ENSLIN, a citizen of the United States, residing at Malden, in the county of Middlesex and State of Massachusetts, have invented certain Improvements in Machines for Ornamenting Leather, of which the following description, in connection with the accompanying drawings, is a specification, like reference characters on the drawings indicating like parts in the several figures.

This invention relates to a machine for producing an ornamental pattern upon leather, the purpose being to enhance its value as, for example, by producing from an inexpensive leather imitations of the more expensive varieties.

Hitherto the ornamentation of leather has been accomplished by such methods as stamping or embossing which require both expensive apparatus and a good grade of leather to be carried out successfully; but with the present machine a cheap piece of leather, such as sheep skin, can be treated at small expense so as to ornament it for use in making such articles as, for example, card cases, pocket books and hand bags.

Leather, as is known, comprises a flesh side which is usually hidden in the finished article and a grain side which is usually the display side; and in order to promote clearness the present invention will be described in connection with these two sides, the flesh and the grain. I have found that by shrinking the flesh side of a piece of leather without shrinking the grain side, or by shrinking the flesh side more than the grain side, a product can be obtained of considerable less area than the original piece which is smooth on the flesh side and is wrinkled or puckered on the grain side, and that this wrinkling or puckering of the grain side can be so produced as to present the appearance of expensive leather.

It is desirable that the shrinking be confined as nearly as possible to the flesh side and produced in such a manner that in the finished piece of leather the flesh side will be smooth and have approximately the same appearance that it had before being shrunk, the wrinkling or puckering being confined to the grain side. In carrying out the process which has been outlined above the piece of leather should be held taut during the shrinking operation so that the natural tend-

ency of the leather to curl when it is shrunk will be resisted; and I have found that if the leather is so held it will pass through the shrinking operation referred to above without having imparted to it any considerable curling or warping, the finished product being substantially as flat as the original, except, of course, for the wrinkling of the grain side.

The present invention relates broadly to a machine for imparting to a piece of leather by the use of a shrinking agent an ornamental surface and to certain details of construction and combinations of parts which will be described in connection with an illustrative machine and pointed out in the appended claims.

Referring now to the accompanying drawings,—Figure 1 is a front elevation of a machine in which the present invention is embodied; Fig. 2 is an elevation of the right hand end as viewed in Fig. 1; Fig. 3 is a plan; Fig. 4 is a detail perspective of the front right hand corner of the machine as viewed in Figs. 1 and 3; Fig. 5 is a detail perspective of the front left hand corner of the machine as viewed in Figs. 1 and 3; Fig. 6 is a detail perspective of the mechanism for moving the gas burner from the front to the rear of the machine and back again, and Fig. 7 is a detail elevation of the split nuts which are alternately caused to engage the feed screws.

Fast to the upper part of the base 1 of the machine is a rectangular frame consisting of four rods 3 (see Figs. 1 and 2) suitably fastened together and each carrying a series of rolls 5 separated by springs 7. Between this frame and a second frame substantially identical with it and located above it (said upper frame being shown complete in Fig. 3) the piece of leather to be treated is gripped.

The manner in which the upper frame is yieldingly urged toward the lower frame so as to grip the stock is shown in detail in Figs. 4 and 5. Referring first to Fig. 4 which shows the front right hand corner of the machine as viewed in Figs. 1 and 3, this corner will be described, it being understood that the rear right hand corner is similar in every way, both corners being shown in Figs. 2 and 3. Pivoted at 9 to the base of the machine is a lug carried by a collar 11 through which is threaded a pin 13, said pin being

held in place by a nut 15. This pin has slidably mounted upon it a bearing 17 which is fast to the upper frame and is guided in its angular movement about the pivot 9 by a yoke 19 which is fast to the lower frame. In order to hold the two frames together at this end the upper frame has two hooks 21 to receive a rod 23 pivoted to the ends of which are links 25. These links at their lower ends are pivoted to arms 27 which are in turn pivoted to the frame of the machine. Springs 29 attached at their upper ends to the arms 27 and at their lower ends to stationary arms 31 serve through the arms 27, links 25, rod 23 and hooks 21 to pull this right hand end of the upper frame down toward the lower frame.

Turning now to the left hand end of the machine as viewed in Figs. 1 and 3 and to the enlarged details illustrated in Fig. 5, the rod 123, hooks 121, links 125, pivoted arms 127, springs 129, and stationary arms 131 are similar to those which have been described in connection with the right hand end of the machine. The pins 33, however, are mounted in a different manner from that of the pins 13. These pins 33 are pivoted at 35 to the base of the machine and are thus adapted to be swung into and out of yokes 37 which are carried by the upper frame. Each pin has at its upper end a head 39 between which and a washer 41 is located a spring 43.

With the construction thus far described the manner in which the piece of leather is held taut during the shrinking operation will be clear. When it is desired to clamp a piece of leather between the frames the front rod 123, is lifted out of the hooks 121, both the rods 23 and 123 having bent portions to serve as handles when desired. The pins 33 are then swung forward out of the yokes 37 after which the upper frame may be swung about the pivots 9 at the rear end so as to separate the two frames for the reception of the piece of leather. After the piece of leather has been placed upon the lower frame the upper frame is swung down again into the position shown in the drawings. Attention is particularly directed to the series of rolls between which the leather is gripped and to the fact that these rolls are freely slidable upon the rods which carry them and are normally held apart by springs. The purpose of this construction is to permit the piece of leather to shrink while at the same time maintaining it taut. It should be noted too that the shrinking of the leather is opposed with approximately uniform force in all directions parallel to its surface.

The shrinking may be accomplished by any suitable shrinking agent, and in the illustrative machine a gas flame is used to which one side of the leather is exposed

momentarily. In the illustrative machine the application of heat takes place progressively across the leather from one edge to the opposite one, but the particular manner in which the heat is applied is immaterial so long as it is properly confined to the treated side. Where an intense heat is used care should be taken, however, not to allow the heating agent to remain for any considerable length of time in operative relation to the leather since, aside from the danger of spoiling the leather by burning it, which is obviously liable to occur, if the heat is allowed to strike through into the grain side said side is liable to shrink equally with the flesh side so that the finished produce will be smooth on both sides and have the same appearance as the original except, of course, as to size. Consequently the heat should be applied only momentarily to the leather and then immediately withdrawn, a result which in the illustrative machine is accomplished by moving the flame across the surface of the leather so as to make the application of heat progressive.

Referring now more particularly to Fig. 6 a gas burner 45 is fast to a traveler 47 which is slidably mounted on rods 49 and is adapted to be moved to and fro from front to back of the machine in order to apply heat to the under side of a piece of leather while said piece is held taut between the frames. This gas burner is shown (see Fig. 1) as of the Bunsen type. The gas is supplied through a flexible tube 51 and is regulated by a cock 53 having a handle 55 which is automatically turned to nearly closed position, whenever the traveler 47 reaches either of its extreme positions, by contacting with pins 57 which are threaded through the sides of the base of the machine so as to be adjustable. A pair of balanced springs 59 (see Fig. 3) arranged between the handle 55 and suitable lugs on the traveler 47 are provided to keep the gas cock 55 wide open except when it is nearly closed by contact with the pins 57. In the position in which the parts of the machine are shown, which is the position of rest, the gas burner is located at the front of the machine and the gas cock is nearly closed, just sufficient gas being allowed to flow to the burner to maintain the flame.

After a piece of leather has been clamped in place between the two frames the traveler 47, which carries the burner, is moved across the under side of the leather one or more times as may be desirable; and in the illustrative machine this movement is automatic in response to movement of a controlling member. To this end two smooth half-bearings 61, 63 are formed on the traveler 47, said half-bearings coöperating with corresponding threaded half-nuts 161 and 163

to receive threaded shafts 65 and 67. The half-nuts 161, 163 are normally held downwardly against supporting ledges 68 (see Fig. 1) and out of contact with the screws 65 and 67 by springs 69. The screws 65 and 67 have threads of the same pitch and inclination but are rotated in opposite directions by intermeshing gears 71, 73 fast respectively to said screws. A grooved pulley 75 fast to the screw 67 furnishes means for applying power to the screws. With the construction thus far described and when power has been applied to the pulley 75 in the direction indicated by the arrow, if the half-nut 161 is moved up to and held in engagement with the screw 65 the traveler 47 will be caused to move from the front to the rear of the machine, and if then the half-nut 161 is lowered and the half-nut 163 raised the traveler will be moved back into the position shown.

The mechanism by which such manipulation of the half-nuts is accomplished is as follows: A shaft 77 rotatably mounted in the base of the machine carries at its front end a handle 79 by which it may be turned and at its rear end an arm 81 the outer end of which is located in position to engage the half-nut 163 when the traveler has been moved to the rear of the machine. A similar arm 83 is fast to a hub 85 which has trunnions 87 mounted in suitable sockets in the base of the machine. Integral with the hub 85 is a second arm 89 pivoted to one end of a link 91 the other end of which is pivoted to an arm 93 on the shaft 77. A spring 95 normally holds these connected parts in the position shown. If now the handle 79 is depressed the arm 83 will lift the half-nut 161 into engagement with the screw 65, and the traveler 47 will start to move toward the rear of the machine. When one of the half-nuts has thus been raised into contact with its screw it must obviously be held in raised position until the traveler has completed its movement across the machine. In order so to hold the half-nuts two locking or separating members 97, 99 are pivoted on a stud 101, which is fast to the traveler, and are continuously urged to move in a clockwise direction, as viewed in Fig. 3, by coiled springs 103, 105 which are fastened at their upper ends to a pin 107 and are then wound about the stud 101 with their free ends bearing against the sides of the locking or separating members 97 and 99 respectively. The outer ends of the members 97 and 99 are thus pressed against the sides of the half-nuts 161, 163 when said half-nuts are in their lowermost position. As soon, however, as one half-nut is raised the end of the corresponding locking member is forced beneath it. In order to push each locking member from beneath its half-nut and thereby permit the half-nut to drop when the traveler

has reached one extreme or the other of its movement, stop pins 109 and 111 adjustably mounted in the base of the machine are so located as to contact respectively with the locking or separating members 97, 99.

The operation of the machine is as follows: The piece of leather is clamped in place with its flesh side down in the manner which has been described. The machine having been started and the gas lighted, the operator depresses the handle 79 thereby connecting the screw 65 with the traveler 47 and causing the traveler to be moved from the front to the rear of the machine. The first portion of the movement of the traveler carries the handle 55 of the gas cock out of range of the stop pin 57 whereby the balanced springs 59 hold said cock wide open. During the last portion of the movement of the traveler the stop pin 57 at the rear of the machine acts automatically to turn down the gas. Referring now to the mechanism which moves the traveler, as soon as the lever 79 has been depressed the locking member 97 is forced beneath the half-nut 161; and when the traveler approaches the end of its movement the stop pin 111 pushes the locking member 97 back and permits the half-nut 161 to drop. If the operator desires to apply further heat to the leather piece he merely depresses the handle 79 again whereupon the traveler is connected with the screw 67 the gas is turned up and the machine comes to rest finally with the parts in the position shown. The operator may continue, if necessary, to repeat the application of the heat to the leather until the desired pattern appears on the grain side.

It will be understood that the machine shown has been chosen for illustrative purposes only and that the terms "flesh side" and "grain side" have been used rather than the terms "one side" and "other side" or "treated side" and "display side" merely to promote brevity and clearness and that either side of the leather, if desired, may be subjected to shrinkage.

In the illustrative machine the shrinking of the leather is opposed with approximately uniform force in all directions, but it should be understood that this is not essential since by varying the magnitude of these forces the pattern produced may be varied, the only essential thing being to hold the leather approximately taut or extended so as to prevent it from curling up.

This application is a continuation so far as common subject-matter is concerned of applicant's co-pending application Serial No. 787,943.

Having thus described my invention, I claim as new and desire to secure by Letters Patent of the United States:

1. A machine of the class described having, in combination, means for holding a

- piece of leather yieldingly so as to permit it to shrink, and means for applying a shrinking agent to one side of the piece so held.
2. A machine of the class described having, in combination, means for holding a piece of leather yieldingly so as to permit it to shrink, and means for applying momentarily to one side of the piece so held a shrinking agent.
10. 3. A machine of the class described having, in combination, means for holding a piece of leather yieldingly so as to permit it to shrink, and means for applying progressively to one side of the piece so held a shrinking agent.
15. 4. A machine of the class described, having, in combination, means for holding a piece of leather extended, said means having provision for permitting said piece to move with respect to it, and means for shrinking one side of the piece so held.
20. 5. A machine of the class described having, in combination, means for yieldingly holding a piece of leather taut, said means being constructed and arranged to oppose with approximately uniform force shrinking by said piece in all directions parallel to its surface, and means for applying to one side of said piece a shrinking agent.
25. 6. A machine of the class described having, in combination, means for yieldingly holding a piece of leather taut, said means being constructed and arranged to oppose with approximately uniform force shrinking by said piece in all directions parallel to its surface, and means for momentarily applying a shrinking agent to one side of said piece.
30. 7. A machine of the class described having, in combination, means for yieldingly holding a piece of leather taut, said means being constructed and arranged to oppose with approximately uniform force shrinking by said piece in all directions parallel with its surface, and means for progressively applying a shrinking agent to one side of said piece.
35. 8. A machine of the class described having, in combination, means for yieldingly holding a piece of leather taut, said means being constructed and arranged to oppose with approximately uniform force shrinking by said piece in all directions parallel to its surface, a source of heat, and means for momentarily exposing said piece to said source.
40. 9. A machine of the class described having, in combination, means for yieldingly holding a piece of leather taut, said means being constructed and arranged to oppose with approximately uniform force shrinking by said piece in all directions parallel to its surface, a source of heat, and means for moving said source across one side of said piece.
45. 10. A machine of the class described having, in combination, means for holding a piece of leather taut, said means being constructed and arranged to permit said piece to shrink while maintaining its tautness, a heating member, and means for causing relative movement between said piece and member first to apply heat to said piece and then to withdraw it therefrom.
50. 11. A machine of the class described having, in combination, means for holding a piece of leather taut, said means being constructed and arranged to permit said piece to shrink while maintaining its tautness, a heating member, and means for moving said member into and out of operative relation to said piece.
55. 12. A machine of the class described having, in combination, means for holding a piece of leather taut, said means being constructed and arranged to permit said piece to shrink while maintaining its tautness, a heating member, means for moving said member across said piece, and means for diminishing the heat when the heating member approaches the end of its movement.
60. 13. A machine of the class described having, in combination, means for holding a piece of leather taut, said means being constructed and arranged to permit said piece to shrink while maintaining its tautness, a heating member, means for moving said member across said piece, and automatic means for diminishing the heat when the heating member approaches the end of its movement.
65. 14. A machine of the class described having, in combination, means for holding a piece of leather taut, said means being constructed and arranged to permit said piece to shrink while maintaining its tautness, a traveler adapted to traverse said piece, a heating member carried by said traveler, and means for operating said traveler.
70. 15. A machine of the class described having, in combination, means for holding a piece of leather taut, said means being constructed and arranged to permit said piece to shrink while maintaining its tautness, a traveler adapted to traverse said piece, a continuously operated member adapted when connected with said traveler to impart movement to it, means under control of the operator for connecting said continuously operated member with said traveler, and automatic means for disconnecting said member and traveler at the end of the traverse.
75. 16. A machine of the class described having, in combination, a pair of frames between which a piece of leather is held, means for causing said frames to grip the piece yieldingly, a source of heat, and means for exposing one surface of said piece to said source.
80. 17. A machine of the class described hav-

ing, in combination, a pair of frames between which a piece of leather is held, means for causing said frames to grip the piece yieldingly, a source of heat, and means for causing said source of heat to travel across one surface of said piece.

18. A machine of the class described having, in combination, a frame comprising a plurality of yieldingly spaced rolls, yielding means for pressing the margin of a sheet of leather upon said rolls, and means for applying to one side of a piece so held a shrinking agent.

19. A machine of the class described having, in combination, means for holding a piece of leather taut while permitting it to shrink, a manually controlled member, and means responsive to movement of said member for causing a shrinking agent to be applied to said piece.

20. A machine of the class described having, in combination, means for holding a piece of leather taut and means for shrinking one side of a piece so held more than the other side in such manner that an ornamental pattern in wrinkles or puckers is produced on said last-named side.

21. A machine of the class described having, in combination, means for yieldingly holding a piece of leather taut while permitting it to shrink, and means for puckering one side of the piece so held while maintaining the other side substantially smooth.

In testimony whereof I have signed my name to this specification in the presence of two subscribing witnesses.
